UNITED STATES PATENT OFFICE.

ELMER D. OGDEN, OF WILCOX, PENNSYLVANIA, ASSIGNOR OF ONE-HALF TO ELMER HOLQUIST, OF WILCOX, PENNSYLVANIA.

GAS-REGULATOR.

1,122,299.

Specification of Letters Patent. Patented Dec. 29, 1914.

Application filed May 2, 1914. Serial No. 835,933.

To all whom it may concern:

Be it known that I, ELMER D. OGDEN, a citizen of the United States, residing at Wilcox, in the county of Elk and State of Pennsylvania, have invented a new and useful Improvement in Gas-Regulators, of which the following is a specification.

This invention relates to a gas regulating device, designed to automatically reduce, or if desired, to entirely cut off the flow of gas to a burner upon the removal of a vessel therefrom, and also to automatically start or increase flow of gas to said burner when the vessel is replaced.

With these objects in view the invention consists of the novel features of construction hereinafter described, pointed out in the claims and shown in the accompanying drawings, in which:

Figure 1 is a sectional side elevation of the device. Fig. 2 is a section on the line 2—2 of Fig. 1.

In these drawings 1 represents a burner and 2 a gas supply pipe to said burner. In the horizontal portion of said pipe is arranged a valve seat 3 adapted to be closed by means of a vertically movable valve 4. A short vertically arranged branch pipe 5 communicates with the pipe 2 in alinement

with said valve seat and said pipe supports a cylindrical vessel 6, the top and bottom of which is formed of some suitable flexible resilient metal. The said vessel carries a stuffing box 7 arranged centrally upon the top of the receptacle and a valve stem 8 is connected at its lower end to the valve 4 and extends upwardly through the pipe 5 centrally and transversely through the receptacle 6 and through the stuffing box 7, the

said stuffing box fitting tightly upon said stem. Pivotaly mounted upon the upper end of the valve stem is a lever 9, one end of which works in the upper slotted portion 10 of a bracket 11, and the other end works in

a slot 12^a formed in a sleeve 12, which sleeve is supported from the vertical portion of the pipe 2. A suitable rod 13 projects upwardly through the burner 1 and at its lower end is pivotally connected to the lever 9 within the sleeve 12. A suitable adjusting screw 14 works through the top of the bracket 11 and bears upon the upper edge of the lever 9.

The screw 14 can be set so that the pressure of gas within the vessel 6 will cause the

valve 4 to seat itself, as shown in Fig. 1, thereby completely cutting off the flow of gas to the burner. But it will be obvious that if it is desired to retain a low flame in the burner when not in use the adjusting screw 14 can be turned down so as to limit upward movement of the lever 9 thereby preventing vertical movement of the stem 8 and the valve 4 to completely cut off the flow of gas. As soon as a vessel is placed upon the burner 1 the weight of the vessel will force the rod 13 downwardly, thereby forcing down the stem 8, as shown in dotted lines and also forcing inwardly the top and bottom and especially the top of the vessel 6. This of course moves the valve 4 into the position shown in dotted lines thereby permitting the free flow of gas to the burner. It will be noted therefore that either the pressure of the gas of itself or the gas pressure combined with the resilience of the top and sides of the vessel, when such material is employed, perform automatically those functions which have heretofore been performed by the mechanical turning of the valve stem either by hand or by directly connecting said valve stem to some movable part provided with springs or counter weights.

An adjusting screw 15 works through the lever 9 and regulates the downward movement of the valve 4 so that the size of the flame can be regulated, the screw 15 bearing at its lower end upon a shoulder 16 formed on the bracket 11. The screw 14 by bearing upon the top of the lever 9 will regulate the amount of projection of the rod 13 through the burner, thereby regulating downward movement of said rod, the lever 9 and the stem 8, this movement being limited by the screw 15. By means of these two screws perfect adjustment may be had of all parts.

What I claim is:—

1. The combination with a gas supply pipe, of a vessel having a flexible top and bottom portion and having free communication with said pipe, a valve in said pipe, a stem for said valve, the stem passing through said vessel, means for securing the stem to said vessel, and means adapted to be depressed by a cooking utensil for depressing said stem.

2. The combination with a burner and a supply pipe having a valve therein, a rod projecting upwardly through said burner, a

horizontally arranged vessel having free communication with said pipe in advance of said valve, said vessel being normally expanded by pressure of gas, a valve stem passing through said vessel, means for connecting said stem with the top of the vessel, and means for connecting said stem with said rod.

3. In a device of the kind described comprising a gas supply pipe, a valve therein adapted to regulate passage of gas through said pipe, a branch pipe in alignment with said valve, a cylindrical vessel mounted upon said pipe, said vessel having flexible sides and being in communication through said

pipe with the gas supply pipe, a stem carried by said valve and passing through the second mentioned pipe transversely through the said vessel, a stuffing box carried by the vessel through which said stem passes, a burner carried by the gas pipe, a lever pivotally connected to said stem, adjustable means for limiting movement of one end of said lever and a rod carried by the other end of the lever and projecting upwardly into said burner.

ELMER D. OGDEN.
